UNITED STATES PATENT OFFICE

HARRY ZIMMERMAN, OF LAKELAND, FLORIDA, ASSIGNOR, BY MESNE ASSIGNMENTS,
TO THE YERGES MANUFACTURING COMPANY, OF FREMONT, OHIO, A CORPORATION
OF OHIO

STITCHED BUFFING WHEEL

Application filed March 14, 1927. Serial No. 175,408.

This invention relates to fabric buffing sections to be assembled into wheels.

This invention has utility when incorporated in sewed fabric buffing disk sections 5 wherein the sewing or stitching lines are in two series for outlining diamond shaped pockets.

Referring to the drawings:

Fig. 1 is a side elevation of a buffing section having mounted thereon buffing disks under the invention herein;

Fig. 2 is a side elevation, with parts broken away, of a plurality of plies of warp and woof fabric assembled by partial stitching into a buffing section;

Fig. 3 is a side elevation of a buffing section having star or diamond formed stitching, the stitching being open for a more soft or loose type of buffing section;

Fig. 4 is a side elevation of a buffing section of a more densely sewed or harder type than the buffing section of Fig. 3;

Fig. 5 is a view in side elevation, with parts broken away, showing bias strip formed buffing section showing diamond or star closed pocket sewing for the assembly of the plies therein as well as the Greek cross open pocket type of sewing;

Fig. 6 is a view of a buff having additional stitching thereon from that shown in Fig. 2;

Fig. 7 is the buff of Fig. 6 with a third series of stitching thereon;

Fig. 8 is a buff with additional diameters over the showing of Fig. 2;

Fig. 9 shows the parallel stitching on a buff over such diameter stitchings of Fig. 8;

Fig. 10 shows the additional parallel series of stitchings on the stitching of the buff of Fig. 9;

Fig. 11 shows radial instead of diametrical stitching;

Fig. 12 shows a first series of stitchings 45 as to the radial stitching of the buff of Fig. 11;

Fig. 13 shows a second series of stitchings partially overlapping the stitchings of the buff of Fig. 12; and

Fig. 14 shows a third series of stitchings

partially overlapping the stitchings of Fig. 12, and Fig. 13.

Mounted on base 1 are bearings 2, 3, carrying shaft 4 on which is mounted pulley 5 driven by belt 6. The shaft 4, as extending through the bearing 2 has thereon collar 7 and a plurality of buffing sections 8 held by collar 9 as set up thereagainst by nut 10 on threaded terminal portion 11 of this buffing jack shaft 4. Upon its opposite end or outboard from the bearing 3 this shaft 4 is shown as having fixed thereon additional collar 7 with a pair of buffing disk sections 8 incompletely assembled so that this does not build up to form a wheel as yet, or as shown at the left of Fig. 1.

Portions of fabric, as canvas, may have sections 12, 13, 14, 15, thereof superposed in general form to provide disks with the warp and woof of adjacent buffing portions 70 offset or staggered initially, and may have a plurality of diameter stitchings 16 intersect axially of the section. In accordance with the invention herein, additional stitching lines 17 is one parallel series and lines 18 75 is a perpendicularly disposed series forming a Greek cross stitching assembly for the disks. Additionally and obliquely disposed thereto, may be third series of parallel stitching 19 having perpendicular thereto parallel 80 stitching lines 20 which are shown as cooperative with the similar stitchings 17, 18, in forming a second Greek cross angularly shifted an acute angle extent sufficiently to produce a star form of stitching. This star 85 form of stitching in cooperation with the diametrical assembling lines produces diamond shaped pockets in the showing of Fig. 3, while in the more dense stitching assembly of the Fig. 4 the lines of the series produce even supplemental diamond shaped pockets. The completed section has central opening 21 for mounting upon arbor or shaft 4.

In the event bias strips 22 are built up in 95 plies say by flat wrapping of a strip of fabric and assembling such flat wrapping by stitchings 23, 24, and with each other by diametrical stitching, such may be faced by a single ply fabric disk 25 with a desired spacing of 100

these different series of parallel stitchings in effecting the diamond shape pocket formations.

The buffering sections are primarily assembled by diametrical stitchings 16 or radial stitchings 26. After such primary stitching, which may be continuous through a plurality of adjacent sections, there may be secondary stitching branching from such primary stitching diverging away from the axis of the disk of the buff section with the acute or obtuse angle toward the disk center or away from the disk center.

The showing in Figs. 6, 7, is of obtuse angle type of V-nested stitchings. The showing in Figs. 9, 10, is of acute angle nested stitchings, while the showing in Figs. 12, 13, 14, is of obtuse angle nested stitchings. In the building up from the second 20 series of stitchings for the overlapping series of stitchings as the tertiary series, such overlapping is shown as complete diamond shaped pockets in the structures of Figs. 4, 5, 7, 10. In the development of the nested 25 V-stitching for producing the nested V-pockets such are parallel to the primary stitching lines 26 as radii, Fig. 11. There are parallel stitching lines 27, 28, as a secondary stitching branching from one radial stitching 26 and parallel to the adjacent radial stitchings 26. From an adjacent radial stitching line 26 there are tertiary stitching lines 29, 30, Fig. 13, partially overlapping as to the V-stitching 27, 28.

35 In completing the diamond pocket forming, branching stitching lines 31, 32, from the remaining radius stitching 26 are applied. These pockets are of diamond form in the various showings, with a corner of 40 the diamond between the radial lines in the arbor opening 21. These diamond shaped pockets from this arbor opening 21 are in diverging radial series with symmetrical series of pockets in their radial extent overlapping or staggered as to adjacent radial 45 series. This means that in the peripheral contour of the buffering section, that as one diamond shaped pocket is being opened, an adjacent diamond pocket is of reduced capacity. It follows that there is accordingly 50 alternate opening of these diamond shaped pockets as peripherally disposed, contributing to a uniformity of peripheral condition in pocket capacity and distribution of 55 the abrading or other carried material.

The utility of this buff may be better appreciated when checked up in comparison with the buff of Yerges Patent, 1,515,818, Nov. 18, 1924, wherein with the same amount 60 of thread and accordingly the same amount of labor, there is produced a harder buff and accordingly one more resistant as against buffering action. Furthermore, the entire elimination of tangential stitching lines 65 avoids production of hard places in the buff

periphery, local to such lines for working flat. This means, of course, a more symmetrical buff with greater production possibilities therefrom for efficiency in operation.

What is claimed and it is desired to secure by Letters Patent is:

A buffering section comprising a plurality of superposed plies of fabric for forming a circular disk, and stitching forming nested V-shaped pockets in series, the stitching of 75 pockets of one series overlapping the stitching of pockets of another series for forming minor closed diamond shaped pockets with the stitching approximating uniformity throughout the buffering section, the points of the V-pockets of both series being directed 80 toward the center of the section.

In witness whereof I affix my signature.
HARRY ZIMMERMAN.
